[57] **CLAIM**

The ornamental design for a venetian blind, sunlight and privacy, as shown and described.

DESCRIPTION

FIG. 1 is a perspective view of a venetian blind, sunlight and privacy showing my new design;

FIG. 2 is a top plan view thereof;

FIG. 3 is a front elevational view thereof;

FIG. 4 is a left side elevational view thereof; the right side being a mirror image thereof;

FIG. 5 is a rear side elevational view thereof;

FIG. 6 is a bottom elevational view thereof;

FIG. 7 is an alternate embodiment of the invention of FIG. 1, the sole difference being in the position of the wands and pull cord;

FIG. 8 is a further embodiment of FIG 1, the sole difference being in the position of the wands; and,

FIG. 9 is yet a further embodiment of FIG. 1, the sole difference being in the position of the wands.
